UNITED STATES PATENT OFFICE.

WILLIAM HOWARD MATTHAI, OF BALTIMORE, MARYLAND, ASSIGNOR TO THE HOMELAND MFG. CO., OF BALTIMORE, MARYLAND, A CORPORATION OF MARYLAND.

HANDLE FOR TOOLS.

Application filed August 5, 1926. Serial No. 127,316.

This invention relates to handles for tools and is particularly designed for use on hand tools such as trowels and hand-cultivators wherein pressure on the handle-end is frequently necessary in the manipulation of the tool.

The object of the invention is to provide a hand tool of the trowel or cultivator type with an integrally-formed tubular handle 10 and to provide that tubular handle with an end guard flap of a novel form and against which the hand may seat with comfort when applying end-thrust or pressure to the tool.

The invention is illustrated in the accompanying drawing wherein,—

Fig. 1 shows the complete tool in perspective.

Fig. 2 illustrates the flat blank from which the tool is formed.

Fig. 3 shows the handle in side elevation.

Fig. 4 illustrates a cross-sectional detail through the guard-end of the handle showing the same as it would appear if viewed on the line 4—4 of Fig. 3, and

Fig. 5 shows the same handle as applied to a hand-cultivating tool.

As the invention resides mainly in the formation of the tubular handle it is immaterial just what form the tool proper may have except that the utility of the invention lies in the fact that when the hand of the manipulator applies end-thrust to the tool the pressure of the hand at the end of the tool may be applied without discomfort.

In the structure disclosed in Figs. 1 to 4 inclusive in the drawing I have shown a tool having the form of a hand trowel wherein the body-part 6 of the tool proper is somewhat of a scoop-shape in that it is concave in cross-section.

The blank from which this trowel-form of tool is produced is shown in Fig. 2, wherein the tool portion 7 of the blank is located at one end while the handle-portion 8 of the blank is located at the opposite end of said blank,—the limits of said two portions being determined by the side notches 9, which produces a narrowed neck 10, between said two portions.

It is immaterial to the present invention as to just when the several operations take place or their order of sequence, it being clear that the neck-part 10, forms the connection between tool-body 6 and the handle 11 and that said handle is bent into

the form of a tube that tapers and enlarges slightly from the neck to the end 12 of the handle. The handle obviously is formed integrally with the tool and has a longitudinal butt-seam 13 along its under side. 60

By preference, I also provide the opposite edges of the handle-portion 8 of the blank with slight semi-circular notches 14, so that when the tubular handle is formed those notches will register at the butt-seam 65 and produce a circular opening 15, in the completed handle by which the tool may be hung upon a nail or hook.

By reference to Fig. 2 of the drawing it will be noted that the handle-end of the 70 blank has a central elongation or projection 16 which, when said end is rolled into tubular form, as in Fig. 1, makes that side of the handle longer than the opposite side so that the longer portion may be bent and 75 worked over the end of the handle to form a convex guard flap. This convex guard flap therefore will project over but will be spaced from the open large end of the tubular handle and, being rounded, will seat in 80 the palm of the hand so that the pressure of the hand may be directed against it when end-thrust is desirable in the manipulation of the tool.

The end guard flap is therefore formed 85 integrally with the handle portion of the tool and curves over but is spaced from said end and it is particularly to be noted that the guard is joined to or projects from that circumferential side of the tubular handle 90 which will be exposed from the upper side of the tool during the manipulation of the latter. In other words, when the tool is being operated the concave side of the body-part 6, will be the front or upper side and the guard flap 17 curves from that same front or upper side of the handle so that its free edge 18, will project or face toward the rear or under side where the seam 13 is located. 100

In the structure disclosed in Fig. 5 of the drawing, the handle end 19 is precisely the same as in the structures of Figs. 1 and 3 but the body part 20, has a series of claws 21 formed thereon to produce a hand cultivator tool instead of a trowel. 105

Having described my invention, I claim,—

1. A hand tool having a tool-portion with a tubular handle extending laterally therefrom said tubular handle having a longitudi- 110

2

nal seam extending to the outer end and at a point diametrically opposite the seam the extreme end of said tubular handle being made longer than the remainder thereof so as to provide material to form an end flap, —said end flap extending over the open end and across the axis of the tubular handle and lying in a crosswise position spaced beyond the outer end of the longitudinal handle-seam and also spaced beyond the rear edge of the shorter end portion of the handle-end.

2. A hand tool having a tool portion with a tubular handle which at its outer end is

shorter around a portion of its circumferential end edge than the remaining portion thereof,—the tubular handle having a side seam whose outer end terminates at the shorter end-edge portion and the longer portion at the said end being bent laterally in a plane spaced from and beyond the shorter edge-portion and forming a single guard flap beyond the said shorter circumferential edge portion.
